UNITED STATES PATENT OFFICE.

JACOB GOLDSTEIN AND ISRAEL BLOCK, OF NEW YORK, N. Y.

OIL-STOVE.

SPECIFICATION forming part of Letters Patent No. 444,748, dated January 13, 1891.

Application filed August 9, 1890. Serial No. 361,519. (No model.)

To all whom it may concern:

Be it known that we, JACOB GOLDSTEIN and ISRAEL BLOCK, citizens of the United States, and residents of New York, in the county of 5 New York and State of New York, have invented certain new and useful Improvements in Oil-Stoves; and we do declare the following to be a full, clear, and exact description of the invention, such as will enable others skilled in 10 the art to which it appertains to make and use the same, reference being had to the accompanying drawings, and to letters of reference marked thereon, which form a part of this specification.

15 Figure 1 of the drawings is a front elevation, partly in section. Fig. 2 is a plan view. Figs. 3 and 4 are detail views; and Fig. 5 is a sectional view on the line X X, Fig. 4.

This invention has relation to oil-stoves; 20 and it consists in the construction and novel arrangement of parts, all as hereinafter set forth.

In the accompanying drawings, the letter A designates the base of the stove, having the 25 convex outward and downward extending skirt a, terminating above in the ring b and below in the feet c. This base is of larger diameter than the cylinder-body B of the stove, and it carries the oil pan or reservoir C, which 30 is solidly secured in the under channel b' of its ring b by means of solder. The base is therefore of extended span and weighty, and it affords an excellent support for the body portion, so that the stove is not liable to be 35 casually overturned. From the base-ring b project upwardly the pointed studs d d and the perforated hinge-lugs d' d', and from said base-ring projects inward the bearing-ledge e for the burner-plate, said ring having "also 40 the catch projections f, adapted to engage notches g of said burner-plate to steady the latter in proper position.

The burner-plate D is cast entire with the 45 elongated wick-tubes h h, having the enlarged convex lower portions h'. Said burner-plate is also cast with the feed-opening k, having the marginal rise or wall k' above the level of the plate and forming a bearing for the pivoted stop k'', which is perforated. Perforations are made at h'' in the ends of the 50 enlarged lower portions of the wick-tubes at the

level of the burner-plate to provide bearings for the journals of the wick-raising devices.

E is the casting, which forms the base of the cylinder-body and the burner-cap in one 55 piece. It is provided with the hinge-lug l, having the convex guard l' for the hinge-pin and the perforated bearing ends l''. It is also formed with feet m, having the recessed bearings m', which engage the pointed upper 60 ends of the studs d when the cylinder-body is in its normal or upright position. The casting is provided with an outer marginal bearing at p to receive the lower edge of the sheet-metal cylinder F, and within is the under 65 ledge p', against which bears the cast perforated plate G, being secured thereto by the central screw bolt or tie H, which extends upward through its central perforation v and through the crown-casting K and the cast 70 frame L. The cast perforated plate G is provided with elongated slots g', through which project the upper portions of the wick-tubes h, as shown.

The crown-casting K is of flaring open- 75 work form, and is provided with an exterior annular seat r to receive the upper edge of the cylinder-body B. This casting is perforated centrally for the passage of the vertical tie-rod H, and on each side of the perforation 80 are the elongated slots K' K', having the depending strengthening-flanges K''.

The doorway of the cylinder-body is provided with a cast frame L, which is formed with a transverse concave flange I', extending inward from its hinge side and covering in the marginal portion of the door-opening on this side to form a seat, as at s, for the hinge-bar t of the door N, said hinge-bar being connected to the door at the ends and 90 having an interval slot s', through which extends the concave flange L'. In this manner is formed a simple and inexpensive hinge, which is nevertheless durable.

This stove may be made in single or double 95 form. When made in double or twin form, the connection between the bases is effected by casting a tie from one skirt a to the other.

Having described this invention, what we claim, and desire to secure by Letters Patent, 100 is—

1. The combination, with the cylinder-body

- B, of the door-frame casting having the curved hinge-flange, and the door having the hinge-bar and the interval slot, substantially as specified.
- 5 2. In an oil-stove, the combination, with the extended base A, channeled underneath and having the oil-pan secured rigidly thereto, its seat-ledge e, its catch projections, and studs, of the burner-plate and its notches, the 10 lower cylinder-casting E, its hinge device, and recessed feet, substantially as specified.
3. The combination, with the lower cylinder-casting E, formed entire with the burner-cap and having the outer marginal bearing and the feet formed with the recessed bearings m', of the cylinder-body, the perforated 15
- cast plate G, the crown-casting K, having the exterior annular flange r, and the central perforation for the tie-rod, the cast frame L, and the said tie-rod extending upwardly through plate G, cast frame L, and crown-casting, substantially as described. 20

In testimony whereof we affix our signatures in presence of two witnesses.

JACOB ^{his} GOLDSTEIN.
^{mark}
ISRAEL BLOCK.
